ATTORNEY

UNITED STATES PATENT OFFICE

JOSEPH C. HOWELL, OF FORT LEE, NEW JERSEY

ADJUSTABLE ARCH SUPPORT

Application filed October 26, 1931. Serial No. 571,235.

My invention relates to improvements in adjustable arch supports, and it consists in the constructions, arrangements and combinations herein described and claimed.

5 The device which forms the subject of this application is an improvement over those devices shown in my pending applications Serial Nos. 524,961 filed March 24, 1931, and 541,649 filed June 2, 1931.

10 The present invention has for its main object the provision of an arch support which will flex when pressure comes upon it, means being provided to prevent the end of the support from cutting into or wearing the inner sole of the shoe.

15 A further object is to provide a covering for that portion of the inner sole upon which the end of the arch would slide were the covering not present, this covering serving 20 as a covering also for an adjustable plate and being replaceable.

25 A further object of the invention is to provide an arch support of the type described in which the rear end of the support is covered by a heel pad, thus preventing the rear end of the arch support from coming in contact with the hose, and providing a substantially continuous surface at the point where the end 30 of the arch support bears on the inner lining of the heel.

35 Other objects and advantages will appear in the following specification and the novel features of the invention will be particularly pointed out in the appended claims.

40 My invention is illustrated in the accompanying drawing forming part of this application, in which:

Figure 1 is a plan view of an arch support 45 constructed according to my invention, as applied to a shoe, certain portions of the shoe being shown in section.

Fig. 2 is an enlarged section on line 2—2 of Fig. 1,

45 Figure 3 is an enlarged section along the line 3—3 of Fig. 2, and,

50 Figure 4 is a plan view of an adjustable plate which is primarily designed as a support for the metatarsal bones, which will result in causing the bones to assume their

natural position when pressure is brought to bear.

In carrying out my invention I provide an arch support 5 of the shape shown in the drawing. It will be noted that this arch support is shorter than ordinary. It is made of any suitable material. The rear end of this plate is rounded as shown at 5a in dotted lines in Figure 1, and is disposed in a recess 6 having a countour substantially the shape of the rounded end 5a, this recess being made in the inner sole 7 of the shoe. A heel pad 8 is disposed over the inner sole and extends over that portion of the arch support in the recess 6 well up on the arch support, so as to give 60 a substantially continuous surface and to prevent the fabric of the hose from being injured by the end of the arch support.

Near the front end of the arch support 5 is an adjustable plate 9 which is ovate in shape, and which is provided with slots 10 extending inwardly from the outer edges of the plate to divide the plate into a series of flexible sections. This plate 9 is riveted or otherwise secured by brads 11 to a head 12, on a hollow cylindrical member 13 which passes through a central opening 14 in the plate 9, and is upset as shown in Fig. 2 to form an additional holding member. The cylindrical member 13 is threaded internally to receive the threaded portion of a screw 15. The latter has an integral flange 16.

A plate 17 is countersunk into the inner sole 7 and has a cylindrical portion 17a which extends toward the bottom of the shoe. The bottom is recessed to permit the flange 16 of the screw 15 to enter, and it is held in place by means of a plate 18 through which the head of the screw 15 projects. The plates 17 and 18 are held together by rivets (not shown because they would not appear in the view) similar to the rivets 19 of the adjustable member to the right in Fig. 2.

The plate 9 is provided with openings 20 for receiving brads or rivets 21, by means of which a leather covering 22 is secured to the plate. This leather covering, as will be seen from Fig. 1, extends beyond the front end of the arch support 5. The cylindrical member 13 has a groove 13a which is arranged to

receive a key 17y in the member 17x for a purpose hereinafter described.

Between the metatarsal arch support and the rear end of the curved arch support plate 5, are adjustable supports which are similar to the metatarsal arch support except that the members 12x which correspond to the member 12 are riveted or otherwise secured directly to the plate 5.

From the foregoing description of the various parts of the device the operation thereof may be readily understood. Plate 5 is flexible to a certain extent, and the arch may be adjusted by means of a screw driver. The turning of any one of the screws 15 will tend to cause a movement of the cylindrical member such as those shown at 13 or 13x, thus raising or lowering the arch 5. In the case of the metatarsal adjustment it will be observed that the arch support 5 is not secured rigidly to the adjusting plate, but rests on the leather covering 22, which is attached to the plate so that when an adjustment is made of the metatarsal plate the arch support 5 will be raised or lowered at this particular point.

It will be seen from this construction that with the rear end of the arch support 5 underneath the heel pad 8 and the front end bearing on the leather covering 22, two important advantages are gained. In the act of walking any movement of the rear end of the plate 5 will be borne by the recessed portion of the inner sole and the fact that the heel pad covers this end will prevent wear on the hose. The leather covering 22 prevents the front end of the arch support 5 from digging into the inner sole and wearing it out. The leather covering receives any thrust which may come on the front edge of the arch support.

It is important from a corrective point of view that adjustment be made for the metatarsal bones and usually this is accomplished by turning the screw 15 until the pressure is at the proper point which can be determined by experiment.

As has been stated before, the key 17y in the slot 13x prevents the rotation of the cylindrical portion 13 or 13x. In order to prevent the screw 15 from working loose and thereby shifting the position of the adjustment, I provide the locking screw 24 which enters the flange 16 as described in my prior applications.

When the leather covering 22 becomes worn it may be removed from the plate 9 and another covering put in its place so that the inner sole of the shoe is kept from wearing.

The action of the segmental plate 9 is more fully described in my co-pending application Serial No. 571,236 filed October 26, 1931.

In order to ventilate the arch support I may provide openings like those shown in Fig. 1 at 25, these openings in the present instance being decorative in the form of initials.

I claim:—

1. The combination with a shoe having an inner sole extending from front to rear thereof, said inner sole having a recess in the heel portion, of an arch support having one end disposed in the recess, a heel pad covering a portion of the arch support and the heel at one end, an adjustable member disposed near the front end of the arch for raising and lowering the latter, and a covering carried by said adjustable member and extending between the front end of the arch support and the inner sole. 70

2. An arch support, a plurality of adjusting devices rigidly secured to the mid portion of said arch support for raising and lowering the latter, an independent adjusting device disposed between said first named adjusting devices and the front of the arch support, said independent adjusting device comprising a plate, a covering carried by the plate and arranged to bear on the underside of the arch support, said covering being extended between the front end of the arch support and the inner sole of the shoe. 80

3. An arch support, a plurality of adjusting devices rigidly secured to the mid portion of said arch support for raising and lowering the latter, an independent adjusting device disposed between said first named adjusting devices and the front of the arch support, said independent adjusting device comprising a plate, a covering carried by the plate and arranged to bear on the underside of the arch support, said covering being extended between the front end of the arch support and the inner sole of the shoe, and means for actuating said adjusting means from the bottom of the outer sole of the shoe. 90

4. The combination with a shoe, of an arch support, an adjusting member carried by the shoe and actuated from the bottom of the outer sole for raising or lowering the front end of the arch support, and a flexible covering carried by the adjustment member and arranged to bear on the underside of the arch support, said covering being extended between the front end of the arch support and the sole of the shoe. 100
